By Myers & Co.

UNITED STATES PATENT OFFICE.

FREDERIC SMITH, OF SULPHUR SPRINGS, OHIO, ASSIGNOR OF TWO-THIRDS
HIS RIGHT TO WILLIAM S. BACON, OF SAME PLACE.

IMPROVEMENT IN BREECH-LOADING FIRE-ARMS.

Specification forming part of Letters Patent No. 158,221, dated December 29, 1874; application filed
April 17, 1874.

To all whom it may concern:

Be it known that I, FREDERIC SMITH, of Sulphur Springs, in the county of Crawford and State of Ohio, have invented certain new and useful Improvements in Breech-Loading Fire-Arms; and I do hereby declare the following to be a full, clear, and exact description of the invention, such as will enable others skilled in the art to which it pertains to make and use it, reference being had to the accompanying drawings, which form part of this specification.

Figure 1 is a longitudinal sectional view, with a portion of the intermediate gun-barrel broken away. Fig. 2 is a plan view of the block-sight. Fig. 3 is a longitudinal sectional view of a part of the adjustable gun-sight.

My invention consists in the employment of a peculiarly-constructed breech-pin as a means of altering breech-loading fire-arms to muzzle-loaders, and an improved adjustable globe or open sight for rendering more convenient and certain the aim of the piece.

A is a cylindrical and adjustable breech-pin which is inserted in the breech of a breech-loading fire-arm, for the conversion of a breech-loading fire-arm into a muzzle-loader, whereby the piece may be loaded and fired as a muzzle-

loader. The breech-pin, being adjustable, can, when desirable, be removed; as is the empty cartridge-shell upon the discharge of the piece as a breech-loader, and the tube or capper B can be capped by the same means, or as ordinarily obtains in breech-loaders for raising the cartridge to its proper place in a line with the bore, or a separate capper can be supplied. In the center of said breech-pin is the small orifice C, which extends longitudinally about one-half its length, and at its termination there is provided a small female screw, into which screws the tube or capper B. The breech-pin is provided with the flange D, which fits into a recess provided in the gun-barrel.

I claim—

The combination and arrangement of the cylindrical breech-pin A, having an orifice, C, therein, and flange D thereon, with the tube B and gun-barrel M, substantially as shown and described.

In testimony that I claim the foregoing I have hereinunto set my hand this 26th day of January, 1874.

FREDERIC SMITH.
